UNITED STATES PATENT OFFICE.

BERT SMITH, OF PASSAIC, NEW JERSEY, ASSIGNOR TO AMERICAN THROTTLE COMPANY INC., OF NEW YORK, N. Y.

BALANCED MULTIPLE THROTTLE.

Application filed April 18, 1927. Serial No. 184,714.

The invention relates to locomotives and more particularly to throttles of the so-called multiple type used in connection with them.

Throttles of this multiple type are most

5 conveniently housed in the same casting with the superheater header. The general arrangement of such a combination header and throttle housing is shown in United States Patent Reissue 16,285 to Ray M. Brown. Improved forms which provide means to balance the throttles are claimed in Ray M. Brown's United States application, Serial 10 No. 24,802, filed April 21, 1925, and in United States application 153,329, filed by Neal T. 15 McKee on December 8, 1926. The present invention constitutes an improved form of structures such as shown in said patent and applications.

A very important factor in arrangements 20 of this type is that of keeping the total distance from front to rear as small as possible. This is necessitated by the limited space available between the front tube sheet of a locomotive and the stack. Headers of the so-called

25 T bolt type are readily kept within the small limits at the designer's disposal but when it is desired to utilize the so-called through-bolt header with its numerous advantages the space limitations offer serious difficulties.

30 The improved form of the Brown application referred to above keeps the dimension referred to within the desirable small limits, but a disadvantage is entailed because of the difficulty of machining the top of the header.

35 The form of the Brown application referred to can be utilized in certain cases, but only if

the space between the front flue sheet and stack is fairly large.

40 It is the purpose of the present invention to provide a novel arrangement of the combined superheater header and throttle housing in which the length from front to back is kept small. The header at the same time is of such form that all the parts that have to be machined are readily accessible for this purpose.

45 Other and more detailed objects of the invention will appear in the course of the following description.

The invention is illustrated in the drawings 50 accompanying the present specification. In these drawings Fig. 1 shows a top view, the right half of it being in section, of a combined header and throttle according to my invention. Fig. 2 shows a fragmentary front view, the left portion being in section on line 2-2

of Fig. 1. Fig. 3 shows a sectional view on line 3-3 of Fig. 1. Fig. 4 shows a section of header of a different form embodying my invention.

The general arrangement is as will be clear 60 from what has been said above similar to that used heretofore. The boiler sheet is shown at 1, the front flue sheet at 2, and the flues at 3. Into these flues 3 extend the superheater elements 4 which are secured to the superheater header 5. This superheater header 5 receives steam from the steam dome through the dry pipe 6.

The header has the usual form of the so-called through bolt type. In this form the 70 transverse chamber 7 which receives the steam from the dry pipe 6 delivers it to the forwardly extending fingers or sub-headers 8-8 from which it flows into the superheater elements 4 by which it is delivered in a super- 75 heated state to the fingers or sub-headers 9-9 intermeshed in the usual way with the first named series of sub-headers 8. From the sub-headers 9 the steam is to be delivered to the two steam pipes 10-10 but such flow 80 is to be controlled by the multiple throttles. These multiple throttles are shown at 11. They consist each of a disc-shaped valve proper 12 from which extends downwardly a stem 13 carrying a cylindrical piston 14. 85 From this piston there extends downwardly a projection 15 while from the disc valve 12 extends upwardly a guide rod 16. The disc valves 12 control openings in the horizontal partition 17 while the pistons 14 reciprocate 90 in the cylindrical apertures 18 in a partition 19. The partitions 17 and 19 divide the valve housing into an upper space 20, a middle space 21 and a lower space 22. The steam pipes 10 communicate by means of the connections 23 with the middle space 21.

This general arrangement of the valve housing is not novel, but is similar to that of the McKee application referred to above.

My invention is concerned more particularly with means for carrying the steam from the fingers or sub-headers 9 to the upper space 20. I provide for this purpose a passage 24 which extends forward under the lower chamber or space 22 and up in front of this 105 same space and in front of the middle space 21 opening into the upper space 20. This space extends along the entire distance from side to side of the header as will be clear from an inspection of Fig. 2 except that the con- 110

nections 23 extend through it as Fig. 1 clearly illustrates. The overall dimension from the front flue sheet 2 to the flanges 25—25 is not increased by the presence of the upward part 5 of the passage 24. When this passage is introduced at the rear of chamber 21 as has been the custom heretofore, chamber 21 is thrown forward so far that the base 40 of the smoke stack 41 interferes with access to 10 the chamber. This is very objectionable, as explained more fully below.

The throttles are actuated in the usual manner by means of the rotatable rod 26 and the fingers 27 secured to it; these fingers coming 15 into contact with the lower ends of the extensions 15. The purpose of the pistons 14 is, as will be apparent to those familiar with this art, to balance the throttles so that they may be readily opened. When these throttles are 20 closed, steam from dry pipe 6 flowing through the header and superheater units reaches the upper space 20 and holds the throttles down. In order to balance them steam must be admitted to the lower space 22. This is effected 25 by means of the small balancing or pilot valve 28 which is opened in advance of all the other valves. When it is lifted from its seat, steam from the upper space 20 flows directly into the lower space 22. The other valves can 30 then be easily raised from their seats.

The extensions 16 on the valves extend into guideways 29 in the caps 30. These caps close 35 openings 31 in the top wall of the throttle housing. Through these openings 31 the valves are readily accessible for insertion, removal, honing, etc. The fit between the extension 16 and the walls of the cylindrical space 29 is a loose one so that the space 29 is filled with steam under boiler pressure, and 40 the steam escaping slowly through the loose fit acts as a cushion preventing a sudden upward movement of the valves when they first open.

Access to the superheater header and in 45 particular to the caps 30 is provided through the opening 43 cut in the smoke-box sheet 42 and normally closed by the cover 44. It will be seen from Fig. 3 that by my arrangement the chamber 21 and throttles 11 lie clear of 50 the stack base, and access can therefore be readily gained for the purpose of inserting, grinding and removing the valves, which is possible only with difficulty in the former arrangement where the passage 24 is to the rear 55 of chamber 21 and the latter therefore lies in part under the stack base.

In Fig. 4 is shown a header of the so-called T bolt type. This type as distinguished from the through bolt type described above is well 60 known to those familiar with locomotive superheaters. The bolt-heads are inserted in longitudinal slots in the header base in the manner well known to those familiar with this art, and do not extend clear through the 65 superheater header. The top of the header

need, therefore, not be machined, and does not need to be accessible. This makes it possible to locate the entire throttle housing directly over the fingers 8 and 9. This will be clear from an inspection of Fig. 4. The fingers 9 deliver their steam directly to the upward riser 24 which delivers it to the upper space 20 just as in the principal form first described. By locating the riser 24 at the front, the dimension from the tube sheet to 70 the flanges 25 is here also kept at a minimum, and the throttle chamber likewise lies back further from the stack base than it would were the passage 20 in the old location.

I claim:

1. In apparatus of the class described, the combination of a locomotive smoke-box; a superheater header in its upper part; said header having a chamber extending transversely across the smoke-box; means to deliver saturated steam from the boiler to said chamber; a series of alined spaced forwardly extending hollow fingers communicating with said chamber; a second set of fingers in the spaces between the first; a plurality of superheater elements connecting the two sets; a second transverse chamber parallel to the first; an apertured partition dividing it into upper and lower spaces; valves controlling said apertures; means to conduct steam from 80 the space below the partition; a smoke-stack base above and forward of the second transverse chamber; and a passage around the front of the second chamber connecting the second set of fingers to the space above the 85 partition, whereby the second transverse chamber lies entirely out of line with the 90 smoke-stack base.

2. In apparatus of the class described, the combination of a locomotive smoke-box; a superheater header in its upper part; said header having a chamber extending transversely across the smoke-box; means to deliver saturated steam from the boiler to said chamber; a series of alined spaced forwardly 100 extending hollow fingers communicating with said chamber; a second set of fingers in the spaces between the first; a plurality of superheater elements connecting the two sets; a second transverse chamber parallel to the 105 first; an apertured partition dividing it into upper and lower spaces; valves controlling said apertures; two forwardly extending steam pipe connections to conduct steam from the space below the partition; and a passage 110 including a portion between said steam pipe connections leading from the second set of fingers to the space above the partition.

3. In apparatus of the class described, the combination of a locomotive smoke-box; a superheater header in its upper part; said header having a chamber extending transversely across the smoke-box; means to deliver saturated steam from the boiler to said chamber; a series of alined spaced forwardly 115

extending hollow fingers communicating with said chamber; a second set of fingers in the spaces between the first; a plurality of super-heater elements connecting the two sets; a second transverse chamber parallel to the first; two partitions dividing it into top, intermediate, and bottom spaces; the upper partition having a series of aligned ports and the lower partition having a corresponding series of 10 aligned balancing cylinders; a plurality of

valves having heads controlling said ports and pistons reciprocating in said cylinders; manually operable means to actuate said valves; means to admit balancing steam into said bottom space; two forwardly extending 15 steam pipe connections from the intermediate space; and a passage extending up in front of the second chamber connecting the second set of fingers to the top space.

BERT SMITH.
